United States Patent Office

Des. 214,625
Patented July 8, 1969

214,625

BUILDING BLOCK

George B. Muse, Hillcrest Drive,
Calhoun, Ga. 30701

Filed May 3, 1968, Ser. No. 11,779

Term of patent 14 years

Int. Cl. D25—01

U.S. Cl. D18—2

FIG. 1

FIG. 2

FIG. 3

FIG. 4

FIG. 5

FIG. 6

FIG. 7

FIG. 8

FIG. 9

FIG. 10

FIG. 11

FIG. 12

FIG. 13

FIG. 14

FIGURE 1 is a top plane view of the building block.
 FIGURE 2 is a bottom plan view of the building block.
 FIGURE 3 is a side elevational view of the building block.

FIGURE 4 is an end elevational view of the building block.

FIGURE 5 is a side cross-sectional view of the building block, taken along lines 5-5 of FIGURE 1.

FIGURE 6 is a side cross-sectional view of the building block, taken along lines 6-6 of FIGURE 1.

FIGURE 7 is a perspective view of the building block, showing the side and end opposite from the side and end shown in FIGURES 2 and 3.

FIGURE 8 is a top plan view of a modified building block.

FIGURE 9 is a bottom plan view of the modified building block.

FIGURE 10 is a side elevational view of the modified block.

FIGURE 11 is an end elevational view of the modified block.

FIGURE 12 is a side cross-sectional view of the modified block, taken along lines 12-12 of FIGURE 8.

FIGURE 13 is a side cross-sectional view of the modified block, taken along lines 13-13 of FIGURE 8.

FIGURE 14 is a perspective view of the modified block, showing the side and end opposite from the side and end shown in FIGURES 2 and 3.

I claim:

The ornamental design for a building block, as shown and described.
